US00D641316S

(12) **United States Design Patent**
Schneiderat

(10) **Patent No.:** US D641,316 S
(45) **Date of Patent:** ** Jul. 12, 2011

(54) **RECHARGING TERMINAL FOR AN ELECTRIC VEHICLE OR THE LIKE**

(75) Inventor: **Ralf Schneiderat**, Gernsbach (DE)

(73) Assignee: **ParkPod GmbH**, Karlsruhe (DE)

(**) Term: **14 Years**

(21) Appl. No.: **29/370,301**

(22) Filed: **Jun. 28, 2010**

(30) **Foreign Application Priority Data**

Dec. 28, 2009 (EM) 001652454-0004

(51) **LOC (9) Cl.** 13-02

(52) **U.S. Cl.** D13/107

(58) **Field of Classification Search** D13/106-110,

D13/118-119, 184, 199; D15/9; 320/103-115

See application file for complete search history.
